UNITED STATES PATENT OFFICE.

ADAM S. KIEFER, OF CLEVELAND, OHIO.

AIR-HEATER.

No. 802,046.

Specification of Letters Patent.

Patented Oct. 17, 1905.

Application filed June 27, 1904. Serial No. 214,300.

To all whom it may concern:

Be it known that I, ADAM S. KIEFER, a citizen of the United States of America, residing at Cleveland, in the county of Cuyahoga and State of Ohio, have invented certain new and useful Improvements in Air-Heaters; and I hereby declare the following to be a full, clear, and exact description of the invention, such as will enable others skilled in the art to which it pertains to make and use the same.

This invention relates to improvements in air-heaters, and pertains more especially to a heater designed for burning natural gas.

The object of this invention is to construct an air-heater of the character indicated which is simple and durable in construction, which has a great air-heating capacity, and in which the products of combustion are advantageously utilized.

With this object in view this invention consists in certain features of construction and combinations and arrangement of parts herein-after described, and pointed out in the claims.

In the accompanying drawings, Figure 1 is a rear side elevation, largely in central vertical section, of an air-heater embodying my invention. Fig. 2 is a vertical section on line 2 2, Fig. 1, looking in the direction indicated by the arrow. Fig. 3 is a top plan in section on line 3 3, Fig. 1. Fig. 4 is a vertical section in detail on line 4 4, Fig. 3.

The upright walls of the casing of my improved air-heater are formed by vertically-arranged metal plates A. The heater has a top B, which is preferably composed of a single casting and rests upon the upper edges of the plates or walls A, which top is provided next the inner sides of the said plates or walls with depending flanges b. The plates A rest upon a base-plate or bottom C, which is provided with upwardly-projecting flanges c next the outer sides of the plates or walls A. The base-plate or bottom C of the heater is provided with legs 8 and is composed, preferably, of a single casting. The parts A, B, and C are assembled and held together in any approved manner. The front of the heater-casing is provided with a doorway 7, normally closed by a suitably-applied door D. The said front is also shown provided near the bottom with air-holes 6.

The interior chamber 10 of the casing, formed by the plates or walls A, top B, and

bottom C, centrally between the top and bottom, contains a heating-burner G, which is arranged horizontally. The chamber 12 of the burner is in communication, preferably centrally and at the bottom, with the pipe H employed in conducting the inflammable gas or fluid fuel to the burner.

Air-conducting flues K are arranged vertically and a suitable distance apart laterally within the lower portion of the chamber 10, and the burner G is suitably supported from the said flues. Each flue K rests at its lower end upon the base-plate or bottom C. Each flue K communicates at its lower end with the atmosphere exteriorly of the heater through an aperture or hole 15, with which the base-plate or bottom C is provided centrally of the lower end of the said flue.

The upper end of each flue K terminates in an upwardly-tapering and upwardly-projecting vertically-arranged nozzle k. Each nozzle k extends vertically through the burner-chamber 12, but is preferably formed integral with the burner.

The burner G is provided in the top wall of its chamber 12 with as many apertures or holes 16 as there are nozzles k to accommodate the location of the said nozzles and the discharge of air by the nozzles upwardly into the flames issuing from the burner around the nozzles during the operation of the burner. The surrounding wall or walls of each aperture or hole 16 are provided with recesses 17, which form orifices communicating with the burner-chamber 12 and discharging upwardly.

The chamber 10 of the heater-casing is provided within its upper portion with as many downwardly-tapering air-flues L as there are air-flues K. The upper air-flues L are preferably integral with and depend from the top B of the stove-casing and communicate at their upper ends with the atmosphere exteriorly of the heater. The flues L depend into the nozzles k of the flues K—that is, each flue L depends into a nozzle k and preferably snugly fits within the upper end of the said nozzle.

The lower portion of each flue L is provided exteriorly with grooves or recesses 20, which extend longitudinally of the said flue and are arranged at suitable intervals around the flues. The surrounding wall of the chamber of each nozzle k is provided with recesses

22, arranged at suitable intervals around the nozzle and extending longitudinally of the nozzle from the lower end to the upper extremity of the nozzle, and the said recesses 5 in the said nozzle preferably alternate with the recesses 20, formed in the air-flue depending into the said nozzle. The recesses 20 in the flues L and the recesses 22 in the nozzles k form the air-outlets of the air-flues K.

10 By the construction hereinbefore described it will be observed that the nozzles k are prevented from being overheated, that ample air is supplied to the flames issuing from the burner around the air-flues L to properly 15 support the combustion, that the said flames impinge against the exterior of the flues L, that the flues L are in communication at their lower ends with the lower air-flues K, and that air passes from within the flues K into 20 the flues L and is heated within the last-mentioned flues, that the air heated within the flues L ascends into the atmosphere exteriorly of the heater, and that the upward flare of the flues L facilitates the escape of heated air 25 from the flues.

I would here remark that the burner is preferably provided with discharge-orifices 13 in addition to the orifices 17; but the last-mentioned orifices are the main discharge-orifices of the burner.

The chamber 10 of the heater-casing is provided at the rear of the heater with an outlet 25 (see Fig. 2) for the products of combustion, from which outlet the said products 30 are conducted off in any approved manner.

What I claim is—

1. An air-heater comprising an upright lower air-flue communicating at its lower end with the atmosphere exteriorly of the heater 40 and terminating at its upper end in an upwardly-projecting and upwardly-tapering nozzle; an upright upper air-flue depending into the aforesaid nozzle and communicating at its lower end with the lower flue and at its 45 upper end with the atmosphere exteriorly of the heater, with the lower portion of the upper flue provided in its exterior with recesses which are spaced around and arranged longitudinally of the said flue; a burner extending around the nozzle and discharging upwardly in proximity to but only exteriorly of the nozzle, and means for supplying the burner-chamber with fluid fuel, and the said nozzle being integral with the burner.
- 55 2. An air-heater comprising an upright lower air-flue communicating at its lower end with the atmosphere exteriorly of the heater and terminating at its upper end in an upwardly-projecting and upwardly-tapering 60 nozzle, with the upwardly-tapering portion of the nozzle provided interiorly with upwardly-discharging recesses; an upright upper air-flue depending into and communicating with

the aforesaid nozzle and communicating at its lower end with the lower flue and at its upper 65 end with the atmosphere exteriorly of the heater, with the lower portion of the upper flue provided in its exterior with upwardly-discharging recesses alternating with the aforesaid recesses in the nozzle; a burner extending and discharging upwardly around but only externally of the nozzle, and means for supplying the burner-chamber with fluid fuel.

3. An air-heater comprising an upright lower air-flue communicating at its lower end with the atmosphere exteriorly of the heater and terminating at its upper end in an upwardly-tapering and upwardly-projecting nozzle, with the wall or walls of the chamber of the said nozzle provided with suitably-spaced recesses which extend from the lower end to the upper extremity of the nozzle; an upright upper air-flue depending into the upper portion of the aforesaid nozzle and communicating at its lower end with the lower flue and at its upper end with the atmosphere exteriorly of the heater; a burner extending around the nozzle and discharging upwardly in proximity to but only externally of the nozzle, and means for supplying the burner with fluid fuel.

4. An air-heater comprising an upright lower air-flue communicating at its lower end with the atmosphere exteriorly of the heater, and terminating at its upper end in an upwardly-projecting and upwardly-tapering nozzle; an upright upper air-flue depending into the upper portion of the aforesaid nozzle and communicating at its lower end with the lower flue and at its upper end with the atmosphere exteriorly of the heater, with the lower portion of the upper flue tapering downwardly and provided in its exterior with recesses which are spaced around and arranged longitudinally of the said flue; a burner extending around the nozzle and discharging upwardly in proximity to but only exteriorly of the nozzle, and means for supplying the burner with fluid fuel.

5. An air-heater comprising an upright lower air-flue communicating at its lower end with the atmosphere exteriorly of the heater and terminating at its upper end in an upwardly-projecting nozzle, with the wall or walls of the chamber of the said nozzle provided with recesses which extend from the lower end to the upper extremity of the nozzle and are arranged at suitable intervals around the nozzle; an upright upper air-flue depending into and snugly filling the upper portion of the aforesaid nozzle and communicating at its lower end with the lower flue and at its upper end with the atmosphere exteriorly of the heater, with the lower portion of the upper flue tapering downwardly and provided in its exterior with recesses which

are spaced around and arranged longitudinally of the said flue and alternate with the recesses in the nozzle; a burner extending around the nozzle and discharging upwardly 5 in proximity to but only externally of the nozzle, and means for supplying the burner with fluid fuel.

In testimony whereof I sign the foregoing specification in the presence of two witnesses.

ADAM S. KIEFER.
